The Linde Air Products Company, a corpora-
tion of Ohio

Application September 20, 1947, Serial No. 141,519

Term of patent 14 years

(Cl. D52—1)

To all whom it may concern:

Be it known that I, Walter D. Teague, a citizen of the United States, residing at Annandale, county of Hunterdon, State of New Jersey, have invented a new, original, and ornamental Design for Fluid Pressure Regulator, of which the following is a specification, reference being had to the accompanying drawing, forming a part thereof.

In the drawing,

Fig. 1 is a side view of a fluid pressure regulator, showing my new design;

Fig. 2 is a left end view of the device shown in Fig. 1;

Fig. 3 is a right end view of the device of Fig. 1; and

Fig. 4 is a top plan view of the regulator shown in Fig. 1.

I claim:
The ornamental design for a fluid pressure regulator, substantially as shown.

WALTER D. TEAGUE.
